Primary Examiner — Holly Baynham(74) Attorney, Agent, or Firm — Kevin D. Jablonski; Lane Powell, PC(57) CLAIM

The ornamental design for jeans, as shown and described.

DESCRIPTION

FIG. 1 is a front view of the jeans.

FIG. 2 is a rear view of the jeans.

FIG. 3 is a side view of the jeans.

FIG. 4 is a second side view of the jeans; and,

FIG. 5 is a top-down view of the jeans.

The broken line showing of the jeans is for the purpose of illustrating portions of the article and forms no part of the claimed design.
